ENERGY TRANSFER CIRCUITS

Nils E. Lindenblad, Port Jefferson, N. Y., assignor
to Radio Corporation of America, a corporation
of Delaware

Application July 28, 1939, Serial No. 287,016

34 Claims. (Cl. 250—36)

This invention relates to energy transfer circuits, and particularly to concentric transmission line circuits having hollow inner conductors for accommodating connections to suitable translation circuits.

One of the objects of the present invention is to provide a concentric transmission line and a circuit therefor by means of which a push-pull action can be translated into push-push action.

Another object of the invention is to provide a concentric transmission line having a hollow inner conductor wherein the length of the coupling lead between the transmission line and a translation circuit outside of the field of the concentric line is brought to an absolute minimum.

Another object of the present invention is to provide an oscillation generator having a single quarter wavelength concentric line controlling a pair of electron discharge devices connected electrically in push-pull relation.

A further object of the invention is to provide a circuit by means of which the two branches of a source of push-pull oscillations may be equally loaded by a single concentric transmission line.

A still further object is to provide a circuit by means of which two branches of a balanced or symmetrical translation device or load may be equally loaded by a single resonance space or chamber.

In brief, the present invention may be said to be based on the appreciation of the fact that the interior of the inner conductor of a concentric line contains no electromagnetic field resulting from the currents between the inner and outer conductors of the concentric line, and may be considered as being divorced from the concentric line in the same manner as the space exterior to the outer conductor of the concentric line is divorced from the action within the concentric line. Due to the fact that there are opposite instantaneous polarities on the interior surface of the outer conductor and on the exterior surface of the inner conductor and the fact that the interior of the inner conductor and the exterior of the outer conductor have no electromagnetic field, I make use of these conditions in the concentric line to obtain from those surfaces of the inner and outer conductors which face each other potentials of opposite polarities. For deriving these opposite instantaneous polarities, a connection is made from the inner surface of the outer conductor through an aperture in the inner conductor into the interior

thereof, and another connection is made from the exterior surface of the inner conductor through an aperture in the outer conductor to the space outside the concentric line. In another embodiment I make use of the same principle to obtain currents of opposite instantaneous polarities from a hollow resonant chamber whose confronting surfaces have opposite instantaneous potentials. This last case, of course, involves 10 no inner conductor, such as is employed in a concentric line, and represents the simplest way of deriving potentials of opposite instantaneous polarities from a tuned circuit.

Other objects and features will appear in the 15 following detailed description of the invention which is accompanied by drawings, wherein:

Figs. 1 and 2 show oscillation generation systems employing a single quarter wavelength tuned concentric line for controlling a pair of 20 vacuum tubes in electrical push-pull relation;

Fig. 3 shows the manner in which a balanced 25 push-pull circuit can be coupled to a single concentric transmission line, and vice versa, without the introduction of impedance irregularities;

Fig. 3a shows, in a manner similar to that of Fig. 3, how a pair of balanced push-pull circuits can be coupled to each other by way of 30 a single concentric transmission line acting as an impedance transformer;

Fig. 4 shows an oscillation generation system 35 wherein the vacuum tube is contained within the interior of the inner conductor of the tuned concentric line resonator, the connections between the electrodes of which and the resonator having a minimum of reactance;

Fig. 4a illustrates the equivalent electrical circuit diagram of Fig. 4;

Fig. 4b illustrates a cross section of an oscillator system of a type similar to Fig. 4, showing 40 the preferred mechanical arrangement for achieving a minimum of reactance in the connecting leads between the vacuum tube and the tuned concentric line; and

Fig. 5 shows a modification of the invention 45 in which potentials of opposite instantaneous polarity are obtained from a hollow resonant chamber.

Referring to Fig. 1, there is shown a concentric resonant line comprising an inner conductor 1 and an outer surrounding conductor 2 connected to the inner conductor 1 at one of its ends by means of end plate 3. Inner conductor 1 is made to be electrically one-quarter of a wavelength long at the desired operating frequency and is hollow for at least a portion of its interior. This

type of concentric line is of the low power factor type (high Q), such as is now well known in the art, reference being made to the article by Clarence W. Hansell entitled "Resonant lines for frequency control," published in "Electrical Engineering," August, 1935, pages 852 et seq. for a more detailed description of the line per se. Coupled to the concentric line 1, 2 by means of connections 5, 6 are a pair of vacuum tubes 7, 8 which are electrically connected together in push-pull relation. The grid of vacuum tube 7 is connected to the inner surface of the outer conductor 2 by means of a connection 5 extending within the interior of the inner conductor 1. The grid of vacuum tube 8 is connected to the outer surface of the inner conductor 1 by means of a connection 6 which extends through an aperture in the outer conductor 2 to the interior of the line. Both connections 5 and 6 connect to the conductors 1 and 2 at points substantially the same distance from the end plate 3 in order that the loops formed thereby may encircle substantially the same amount of flux within the concentric line in order to derive therefrom equal loading for the grids of the vacuum tubes. Due to the fact that there is a potential difference between the outer surface of inner conductor 1 and the inner surface of outer conductor 2, and because lead 5 enters the space between the concentric conductors in one direction of potential gradient while conductor 6 enters the space between conductors 1 and 2 from an opposite direction of that same potential gradient, there will be produced on leads 5 and 6 equal potentials of opposite instantaneous polarities. A parallel tuned output circuit 9 is shown connected between the anodes of the vacuum tubes 7 and 8 to the electrical mid point of which there may be applied a suitable positive polarizing potential for these anodes. The exterior of the concentric line 1, 2 is shown by-passed to ground through a condenser 10 in order that suitable grid bias may be supplied through the choke coil 11 to the grids via the concentric line. The condenser 10 is of course strictly not a necessary item since all surfaces exterior to the field of the resonant line are intrinsically at zero potential. It may, however, be well to include this condenser since it helps keep the line from becoming externally energized from external stray fields. This grounding will be more effective if several condensers are connected at distributed points along the exterior surface of the exterior conductor. It will be noted that the quarter wavelength concentric line of Fig. 1 illustrates one advantageous method of controlling a push-pull oscillator by means of a tuned concentric line.

Fig. 2 is similar to Fig. 1, except that the grids of vacuum tubes 7 and 8 are capacitively coupled to the concentric line 1, 2 by means of condensers 12 and 13, instead of the direct coupling shown in Fig. 1. The exterior surface of the concentric line of Fig. 2 is here shown directly connected to ground since the condensers 12 and 13 now isolate the grids 5 and 6 from the conductors of the concentric line. Bias for the grids of vacuum tubes 7 and 8 is obtained by means of a choke coil 11 connected between leads 5 and 6. From the mid point of the choke coil a connection extends to a suitable source of grid bias.

Fig. 3 illustrates a method of connecting a suitable load circuit, here illustrated as a quarter wave radiator 15, to a balanced push-pull source of oscillations such as a transmitter 16, shown conventionally in box form. The radiator 15 is

integral with and forms part of the inner conductor of a concentric transmission line having an outer conductor 17 connected thereto by means of an end plate 18 at a point removed from the effective radiating portion. The push-pull transmitter is coupled to the single concentric line 17 and to radiator 15 by means of a balanced circuit composed of a pair of transmission lines 19 and 20, the inner conductors of which connect to the single transmission line in a manner similar to that shown in Figs. 1 and 2. It will be seen that the inner conductor of concentric line 19 is connected to the inner surface of outer conductor 17, while the inner conductor of concentric line 20 is connected to the outer surface of inner conductor 15 at points equally spaced from the end plate 18. The inner conductor of concentric line 19 is disposed within the interior of the inner conductor 15. In effect, the quarter wavelength radiator 15 at the upper end of line 17 is an unbalanced circuit which is coupled to the balanced circuit 19, 20. It is preferred that the points of connection of the inner conductors of the concentric transmission lines 19 and 20 to the conductors 17 and 15 be spaced one-quarter of a wavelength from the end plate 18 in order that such points of connection be points of high impedance to currents tending to flow to the end plate 18. Between the conductors 15 and 17 the instantaneous directions of the currents are illustrated by means of the arrows on the conductors of lines 19, 20, 15 and 17. It should be noted that the currents on the inner conductors of transmission lines 19 and 20 are in opposite directions, thus giving a push-pull effect, although from an impedance standpoint both transmission lines 19 and 20 are in parallel relation. It should also be noted that the current on the outer surface of conductor 15 becomes the shell current of the inner conductor of transmission line 19, and also becomes the center conductor current of the transmission line 20. Because of the quarter wavelength spacing to the end plate 18, current cannot flow on the outer surface of transmission line 15 below the aperture through which the inner conductor of line 19 extends, nor below the junction point of the conductor 15 with the inner conductor of transmission line 20. Similarly, the central conductor current of transmission line 19 and outer shell current of transmission line 20 become the current on the inner surface of conductor 17, this current also being prevented from flowing to the end plate 18 because of the quarter wavelength spacing shown in the drawings. The effective radiating portion of conductor 15 is one-quarter wavelength, as measured from the open end to the immediately adjacent end of the conductor 17. Both the radiator 15 and the concentric line comprising conductors 17 and 15 each have an impedance equal to Z, while the impedances of each of the transmission lines 19 and 20 are 2Z. Since the transmission lines 19 and 20 are electrically in parallel, the combined effect of the impedances of 19 and 20 is equal to Z, thus introducing no impedance irregularities at the junction points between the transmission lines 19 and 20 and the single concentric line 17, 15. It will be obvious that the lower portion of line 17 between end plate 18 and a point one-quarter wavelength ($\lambda/4$) from this end plate is, in effect, a concentric line resonator containing standing waves, while that portion of line 17 above the concentric line resonator contains traveling waves, since the load 15 is

matched to the line 17 to form a non-reflective termination therefor.

Fig. 3a shows a combination of an arrangement shown in Fig. 3 and that illustrated in Fig. 5 of my copending application Serial No. 183,571, filed January 6, 1938. In Fig. 5 of my copending application supra there is shown an arrangement for connecting a single transmission line of impedance Z in push-pull relation to a pair of branched transmission lines each of them an impedance $Z/2$. In this last case, the branched lines are in series with respect to the single transmission line, and no impedance irregularities are introduced because of the provision of a quarter wavelength sleeve surrounding the single transmission line and connected to the outer conductors of both the single transmission line and the branch transmission lines. Fig. 3a of the present application shows the two branch transmission lines each labeled $Z/2$ in series relation with respect to a single main feeder Z , the latter in turn being fed by two other transmission lines each having an impedance $2Z$ in parallel to each other and extending to a push-pull transmitter 16. The two transmission lines $2Z$, $2Z$ are in push-pull relation to each other although in parallel with respect to the main transmission line Z . The quarter wavelength sleeve 21 which surrounds the single concentric transmission line Z at its upper extremity prevents unbalance between the branch lines $Z/2$ and the main transmission line Z , enabling the free end of the transmission line Z to assume the potentials required for balancing the branch lines with respect to each other. The instantaneous currents in the transmission lines are illustrated by the arrow marks. Since the letter Z represents the impedance of the lines, it will be seen that Fig. 3a shows one method of connecting two transmission lines each of impedance $2Z$ to two branch lines each of impedance $Z/2$, thus effecting an impedance transformation of 4:1, and without introducing impedance irregularities.

Fig. 4 shows a resonant concentric line having an inner hollow conductor 1' and a surrounding conductor 2' suitably coupled together to form a tuned frequency stabilizing circuit for the vacuum tube oscillator T located within the interior of inner conductor 1'. The conductors 1' and 2' are connected together at one end by metallic end plate 3' which is grounded for radio frequency energy, and capacitively coupled together at the other end by an adjustable metallic plate 25 whose position determines the tuning of the resonant concentric line. The grid of tube T is coupled to a suitable point on the inner surface of outer conductor 2' by means of a lead 26 extending through an aperture in conductor 1'. The anode is grounded from a radio frequency standpoint by means of lead 31. The filament leads 28, 28 also pass through apertures in the inner conductor 1' and are coupled to points on the inner surface of the outer conductor 2' which have less radio frequency potential than the point of connection to the grid lead 26; that is, the grid is arranged to have greater coupling to conductor 2' than the filament. It should be noted that leads 26, 31 and 28, 28 are insulated from the conductors of the resonant concentric line from a direct current standpoint by means of the spacing between the plates 29 associated with these leads and the conductors of the line, although capacitively coupled to these conductors of the concentric line by paths of low impedance to radio frequency en-

ergy. In this manner, it is possible to supply the electrodes of the vacuum tube T with suitable polarizing potentials. The equivalent electrical circuit for Fig. 4 is shown in Fig. 4a, which clearly illustrates that the grid of tube T is excited periodically at higher radio frequency potentials than, but in phase with the filament for best oscillating conditions.

The arrangement of Fig. 4 has the advantage of enabling minimization of reactance in electrode leads to the vacuum tubes, and also minimization of lead lengths. One way of reducing the reactance and lengths of electrode leads to a minimum in this arrangement is illustrated in Fig. 4b which shows a cross-section of Fig. 4 with certain mechanical details included. The lead 26 to the grid electrode of tube T is extremely short and is connected to a metallic segment 29 of relatively wide area mounted upon another metallic segment 38 but insulated therefrom by a mica layer 39. Segment 38 is directly connected mechanically to the inner surface of outer conductor 2' and is capacitively coupled to segment 29 forming a path of low impedance to radio frequency energy thereto. If desired, the filament leads 28, 28 may be similarly coupled to conductor 2' of the resonant concentric line.

Fig. 5 illustrates a high frequency tuned circuit of low power factor (high Q) in the form of a metallic resonant chamber 32, here shown as a right circular cylinder having flat top and bottom surfaces, with means for deriving therefrom equal potentials of opposite instantaneous polarities. A resonant chamber of this general type, which may also take the form of an hour-glass or sphere, is described in detail in the copending application of Philip S. Carter, Serial No. 249,711, filed January 7, 1939. For exciting the resonant chamber 32 there is provided any suitable source of oscillations 33, here shown conventionally in box form, coupled inductively to the chamber by loop 34. Connections 30 and 31 connect with oppositely located surfaces and extend through opposite sides of the chamber between which there is a potential gradient. These connections thus have produced in them opposite polarities which may be utilized in any suitable vacuum tube translation circuit, such as an amplifier, push-pull or single ended, detector etc., or a load circuit.

What is claimed is:

1. In combination, a concentric line whose inner and outer conductors have waves of opposite instantaneous polarities thereon, said inner conductor being hollow for at least a portion of its length, a connection from the inner conductor passing through an aperture in the outer conductor, and a connection from said outer conductor passing through an aperture in said inner conductor into the hollow portion thereof, both of said connections extending to a translation circuit.
2. In combination, a resonant circuit having a pair of conducting surfaces separated solely by space, means for producing in said chamber a periodically repeating electromagnetic field and a difference in potential between said pair of surfaces, a connection from one of said surfaces passing through an aperture in the other surface, and a connection from said last surface passing through an aperture in said first surface, both of said connections extending to translation apparatus.
3. A system in accordance with claim 2, characterized in this that said resonant chamber is a

right circular cylinder, and said translation apparatus includes a vacuum tube circuit.

4. In combination, a concentric line resonator having a hollow inner conductor and a hollow outer conductor suitably coupled together to form a tuned circuit, a pair of vacuum tubes, a connection from a cold electrode of one vacuum tube extending through the interior of said inner conductor and through an aperture in said inner conductor to couple to a point on the inner surface of said outer conductor intermediate the ends of said outer conductor, and a connection from the corresponding cold electrode of said other vacuum tube passing through an aperture in said outer conductor to a point on said inner conductor intermediate the ends of said inner conductor.

5. In combination, a concentric line resonator having a hollow inner conductor and a hollow outer conductor, an end plate coupling together one end of one conductor to the adjacent end of the other conductor, a pair of electron discharge devices, a connection from an electrode of one device extending through the interior of said inner conductor from the end thereof at which said end plate is located and through an aperture in said inner conductor to couple to a point on the inner surface of said outer conductor intermediate the ends of said outer conductor, and a connection from a corresponding electrode of said other device passing through an aperture in said outer conductor to couple to a point on said inner conductor intermediate the ends of said inner conductor, said points being substantially equally spaced from said end plates.

6. An oscillator system in accordance with claim 5, characterized in this that said connections couple to the grids of said devices, said devices having anodes between which there is provided a parallel tuned circuit.

7. An oscillation system in accordance with claim 5, characterized in this that said devices each include a grid and an anode, said connections being coupled at one end to said line resonator and at their other ends to said grids, a path of low impedance from said end plate to a point of zero radio frequency potential, and a tuned circuit coupled to the anodes of said devices.

8. In combination, a resonant chamber in the form of a closed conducting surface having a pair of substantially flat surfaces separated by etheric space, said pair of flat surfaces having a potential gradient therebetween, vacuum tube apparatus, a connection from said vacuum tube apparatus passing through an aperture in one of said flat surfaces and coupling to the other of said flat surfaces, and another connection from said vacuum tube apparatus passing through an aperture in said last flat surface and coupling to the first of said flat surfaces.

9. A system in accordance with claim 8, characterized in this that the couplings between said connections and said flat surfaces are conductive for direct current.

10. In combination, a concentric transmission line having a hollow inner and a hollow outer conductor, a path of low impedance between said conductors at one end, a load circuit at the other end of said transmission line, high frequency vacuum tube translating apparatus, a connection from said translating apparatus passing through the interior of said hollow inner conductor at the end at which said path of low impedance is located and passing through an aperture in said

inner conductor to a point on the inner surface of said outer conductor, and another connection from said translating apparatus passing through an aperture in said outer conductor to a point on the outer surface of said inner conductor, said apertures and said points of connection being located substantially one-quarter of a wavelength from said path of low impedance, whereby said points of connection are points of high impedance to currents tending to flow over said inner and outer conductors toward said path of low impedance and the currents in said connections are in opposite directions.

11. Apparatus in accordance with claim 10, characterized in this that said connections constitute the inner conductors of concentric transmission lines, the outer conductor of one of which is a continuation of the inner conductor of said first concentric line and the outer conductor of the other of which communicates with the interior of the outer conductor of said first concentric line at the aperture in said last outer conductor, whereby said concentric lines constituting said connections are electrically in parallel with respect to the first concentric line.

12. Apparatus in accordance with claim 10, characterized in this that said load is a quarter wavelength radiator, and said translating apparatus is a push-pull radio transmitter.

13. In combination, a concentric transmission line having a hollow inner and a hollow outer conductor, a path of low impedance between said conductors at one end, a load circuit at the other end of said transmission line, high frequency vacuum tube translating apparatus, a connection from said translating apparatus passing through the interior of said hollow inner conductor at the end at which said path of low impedance is located and passing through an aperture in said

inner conductor to a point on the inner surface of said outer conductor, and another connection from said translating apparatus passing through an aperture in said outer conductor to a point on the outer surface of said inner conductor, said apertures and said points of connection being located substantially one-quarter of a wavelength from said path of low impedance, whereby said points of connection are points of high impedance to currents tending to flow over said inner and outer conductors toward said path of low impedance and the currents in said connections are in opposite directions, said connections constituting the inner conductors of concentric transmission lines, the outer conductor of one of which is a continuation of the inner conductor of said first concentric line and the outer conductor of the other of which communicates with the interior of the outer conductor of said first concentric line at the aperture in said last outer conductor,

whereby said concentric lines constituting said connections are electrically in parallel with respect to the first concentric line, additional connections extending from the conductors of said first concentric line at their other end, said additional connections also constituting the inner conductors of concentric lines which are electrically in series with respect to said first transmission line, the outer conductors of said additional concentric lines being connected to the outer conductor of said first concentric line through a quarter wavelength sleeve surrounding the last end of said first line.

14. In combination, a conductive boundary enclosing a space, means for producing in said enclosed space a variable electromagnetic field

which produces an internal voltage gradient across said space, said boundary comprising confronting surfaces each of which is provided with an aperture, said apertures being on an imaginary straight line passing transversely to the longest axis of said boundary, connections from the exterior of said boundary extending through said apertures to points on said confronting surfaces which carry potentials of desired relative magnitudes and which have a desired phase with respect to the direction of said internal voltage gradient, and a translation circuit coupled to said connections.

15. The combination with a balanced two conductor system, of a coaxial resonator having an inner and an outer conductor coupled together at one end through a path of low impedance to energy of the operating frequency, one conductor of said balanced system being connected to the outer surface of said inner conductor and extending across the space between said inner and outer conductors and the other conductor of said balanced system being connected to the inner surface of said outer conductor and also extending across the space between said inner and outer conductors, the points of connection of said conductors of said balanced system to said resonator being such that the impedance presented by said resonator to each side of said feeder is the same.

16. In combination, a conductive boundary enclosing a variable electromagnetic field, the interior space thus being traversed by a voltage gradient whereas the exterior space is void of such gradient, said boundary having a pair of apertures on opposite sides of said space and which are substantially the same distance from the ends of said boundary, connections externally of said boundary passing through said apertures and connected through leads of minimum length to the inner surfaces of said boundary on opposite sides of said space, said apertures and the points of connection to the inner surfaces of said boundary being so located that the connections carry potentials of desired relative magnitudes and which are in phase with or reciprocal to the direction of the internal voltage gradient, and a translation circuit coupled to said connections.

17. In combination, a conductive boundary enclosing a variable electromagnetic field, the interior space thus being traversed by a voltage gradient whereas the exterior space is void of such gradient, said boundary having a pair of apertures on opposite sides of said space and which are substantially the same distance from the ends of said boundary, connections externally of said boundary passing through said apertures and connected through leads of minimum length to the inner surfaces of said boundary on opposite sides of said space, said apertures and the points of connection to the inner surfaces of said boundary being so located that the connections carry potentials of desired relative magnitudes and which are in phase with or reciprocal to the direction of the internal voltage gradient, the interior space of said conductive boundary having such dimensions that energy storage by resonance is obtained, and an electron discharge device circuit connected to said connections.

18. In combination, a conductive boundary enclosing a variable electromagnetic field, the interior space thus being traversed by a voltage gradient whereas the exterior space is void of such gradient, said boundary having a pair of apertures on opposite sides of said space, connections externally of said boundary passing through said apertures and

connected to the inner surfaces of said boundary on opposite sides of said space, said apertures and points of connection to the inner surfaces of said boundary being so located that the connections carry potentials of desired relative magnitudes and which are in phase with or reciprocal to the direction of the internal voltage gradient, the space within said conductive boundary containing no conducting material, whereby said conductive boundary forms a wave guide or resonant chamber, and a translation circuit coupled to said connections.

19. The combination with a balanced two-conductor system, of a coaxial resonator having an inner and an outer conductor coupled together at one end through a path of low impedance to energy of the operating frequency, one conductor of said balanced system being connected to the outer surface of said inner conductor and extending across the space between said inner and outer conductors and the other conductor of said balanced system being connected to the inner surface of said outer conductor and also extending across the space between said inner and outer conductors, the points of connection of said conductors of said balanced system to said surfaces being the same distance from one end of said resonator.

20. In combination, a balanced circuit each side of which comprises a coaxial line, an unbalanced circuit, and a concentric line whose inner and outer conductors are coupled together at one end by a path of low impedance to the operating frequency coupled between said balanced and unbalanced circuits, a connection from the inner conductor of one of said coaxial lines to a point on the outer surface of the inner conductor of said concentric line which is approximately one-quarter of a wavelength from said one end, a connection from the inner conductor of said other coaxial line to a point on the inner surface of the outer conductor of said concentric line which is also approximately one-quarter of a wavelength from said one end, and means for connecting said unbalanced circuit to the inner conductor of said concentric line.

21. The combination with a balanced two-conductor feeder line, of a coaxial line having an inner and an outer conductor, one conductor of said feeder being connected to the outer surface of said inner conductor and the other conductor of said feeder being connected to the inner surface of said outer conductor, the points of connection of said feeder conductors to said surfaces being one-quarter wave-length from one end of said coaxial line.

22. In combination, a concentric line resonator having a hollow inner conductor and a hollow outer conductor suitably coupled together to form a tuned circuit, a pair of vacuum tubes, a connection from a cold electrode of one vacuum tube extending through the interior of said inner conductor and through an aperture in said inner conductor to couple to a point on the inner surface of said outer conductor intermediate the ends of said outer conductor, and a connection from a cold electrode of said other vacuum tube passing through an aperture in said outer conductor to a point on said inner conductor intermediate the ends of said inner conductor.

23. In combination, a concentric line resonator having a hollow inner conductor and a hollow outer conductor suitably coupled together to form a tuned circuit, a pair of vacuum tubes, a connection from a cold electrode of one vacuum

tube extending through the interior of said inner conductor and through an aperture in said inner conductor to couple to a point on the inner surface of said outer conductor intermediate the ends of said outer conductor, and a connection from a cold electrode of said other vacuum tube passing through an aperture in said outer conductor to a point on said inner conductor intermediate the ends of said inner conductor, said points on said inner and outer conductors being substantially equally distant from one end of said concentric line resonator.

24. In combination, a balanced circuit each side of which comprises a coaxial line, an unbalanced circuit, and a concentric line coupled between said balanced and unbalanced circuits, a connection from the inner conductor of one coaxial line of said balanced circuit to the inner conductor of said concentric line, a connection from the inner conductor of the other coaxial line of said balanced circuit to the inner surface of the outer conductor of said concentric line, the outer conductors of said coaxial lines being connected together, and a connection from said unbalanced circuit to the inner conductor of said concentric line.

25. A system in accordance with claim 24, characterized in this that the outer conductors of said coaxial lines of said balanced circuit are connected to the outer conductor of said concentric line.

26. In combination, a balanced circuit each side of which comprises a coaxial line, an unbalanced circuit also comprising a coaxial line, and a concentric line coupled between said balanced and unbalanced circuits, a connection from the inner conductor of one coaxial line of said balanced circuit to the inner conductor of said concentric line, a connection from the inner conductor of the other coaxial line of said balanced circuit to the inner surface of the outer conductor of said concentric line, and a connection from the inner conductor of the inner conductor of the coaxial line of said unbalanced circuit to the inner conductor of said concentric line, the outer conductors of all said coaxial lines being connected to the outer conductor of said concentric line.

27. The combination with a balanced two-conductor system, of a coaxial resonator having an inner and an outer conductor coupled together at one end through a path of low impedance to energy of the operating frequency, one conductor of said balanced system being connected to the outer surface of said inner conductor and extending across the space between said inner and outer conductors and the other conductor of said balanced system being connected to the inner surface of said outer conductor and also extending across the space between said inner and outer conductors, the points of connection of said conductors of said balanced system to said surfaces being each substantially one-quarter of a wavelength at the operating frequency from one end of said resonator.

28. In combination, a concentric line whose inner and outer conductors have waves of opposite instantaneous polarities thereon, said inner conductor being hollow for at least a portion of its length, a short circuiting element across the conductors of said concentric line, a connection from the inner conductor passing through an aperture in the outer conductor, and a connection from said outer conductor passing through an aperture in said inner conductor into the hollow portion thereof, both of said connections extending

to a translation circuit, the junction points of said last connections to the conductors of said concentric line being each an odd multiple including unity of a quarter wavelength at the operating frequency away from said short-circuiting element.

29. In combination, a conductive boundary enclosing a variable electromagnetic field, the interior space thus being traversed by a voltage gradient whereas the exterior space is void of such gradient, said boundary having a pair of apertures on opposite sides of said space and which are substantially an odd multiple including unity of one-quarter wavelength at the operating frequency from one end of said boundary, connections externally of said boundary passing through said apertures and connected through leads of minimum length to the inner surfaces of said boundary on opposite sides of said space, said apertures and the points of connection to the inner surfaces of said boundary being so located that the connections carry potentials of desired relative magnitudes and which are in phase with or reciprocal to the direction of the internal voltage gradient, and a translation circuit coupled to said connections.

30. In combination, a balanced circuit, each side of which comprises a coaxial line, an unbalanced circuit, and a concentric line resonator coupled between said balanced and unbalanced circuits, a connection from the inner conductor of one coaxial line of said balanced circuit to the outer surface of the inner conductor of said resonator, a connection from the inner conductor of the other coaxial line of said balanced circuit to the inner surface of the outer conductor of said resonator, and means for connecting said unbalanced circuit to the inner conductor of said resonator.

31. In combination, a balanced circuit, an unbalanced circuit, and a concentric line resonator coupled between said balanced and unbalanced circuits, a connection from one side of said balanced circuit to a high voltage point on the outer surface of the inner conductor of said resonator, a connection from the other side of said balanced circuit to an adjacent point on the inner surface of the outer conductor of said resonator, both of said connections encircling substantially the same amount of flux within said resonator, and a connection from said unbalanced circuit to said resonator.

32. In combination, a tuned oscillatory circuit in the form of a resonant hollow enclosure having a pair of spaced conducting surfaces adapted to have opposite instantaneous polarities thereon, a balanced circuit, an unbalanced circuit, connections from both sides of said balanced circuit to said spaced conducting surfaces, and means coupling said unbalanced circuit to said resonant hollow enclosure.

33. In combination, a balanced circuit, an unbalanced circuit, and a concentric line resonator coupled between said balanced and unbalanced circuits, a connection from one side of said balanced circuit to a point on the outer surface of the inner conductor of said resonator, a connection from the other side of said balanced circuit to a point on the inner surface of the outer conductor of said resonator, both of said connections encircling substantially the same amount of flux within said resonator, and a connection from said unbalanced circuit to a point on the inner conductor of said resonator.

34. In combination, a balanced circuit, an un-

balanced circuit, and a concentric line resonator coupled between said balanced and unbalanced circuits, a connection from one side of said balanced circuit to the outer surface of the inner conductor of said resonator, a connection from the other side of said balanced circuit to the inner surface of the outer conductor of said res-

onator, both of said connections encircling substantially the same amount of flux within said resonator, and a connection from said unbalanced circuit to a point on the inner conductor of said resonator.
